UNITED STATES PATENT OFFICE.

NILS E. NORSTROM, OF CHICAGO, ILLINOIS.

PARTY-LINE TELEPHONE EXCHANGE.

Application filed September 6, 1921. Serial No. 498,689.

To all whom it may concern:

Be it known that I, NILS E. NORSTROM, a citizen of the United States of America, and a resident of Chicago, county of Cook, 5 and State of Illinois, have invented certain new and useful Improvements in Party-Line Telephone Exchanges, of which the following is a specification.

My invention relates to party line 10 telephone exchanges, and has for its object improvements in such exchanges.

In the accompanying drawings—

Fig. 1 is a plan of a part of the central office mechanism;

15 Fig. 2 is a side elevation of the same;

Fig. 3 is a sectional elevation on line 3—3 of Fig. 1;

Fig. 4 is an enlarged section on line 4—4 of Fig. 3;

20 Figs. 5 and 6 are similar sections with the parts in slightly different positions;

Fig. 7 is a section on line 7—7 of Fig. 1;

Fig. 8 is a section on line 8—8 of Fig. 7;

25 Figs. 9 and 10 are elevations of contact springs shown to the right in Fig. 1;

Fig. 11 is a diagram of the central office apparatus and a part of one party line extending therefrom; and

30 Fig. 12 is a condensed diagram of one of the local stations.

Supported on a bed 11 are standards 12, 13 and 14. In the standard 12 is a shaft 15 which has a cam 16 on one end, and a worm gear 17 on the other end. A constantly running worm 18 engages the gear 17 to keep it constantly running. Supported on a standard 19 are two sets of contact springs which have their electrical connections shifted back and forth by the cam 16 once 40 during each revolution of the shaft 15. This operation will be explained more fully in connection with the description of the circuits.

Supported in the standard 13 is a shaft 45 which has a disk 20 on one end, and in the face of this disk near its periphery is a series of equally spaced holes 21. A train of gears 22 connects the shaft of disk 20 with the shaft 15 so that the said disk is also constantly driven. This gearing is so arranged that during the time when the shaft 15 is 50 making one complete revolution, the disk 20

moves the distance between one hole 21 and the next adjacent one.

Secured to the standard 13 by screws 22 55 and 23 (Fig. 3) is a metal plate 24, and secured to this plate by screws 23, 25 and 26 is an arc-shaped piece of insulation 27 in which are contact pins 28. On the standard 13 is a stationary arm 29 which has on its 60 outer end a stop pin 30.

Supported in the standard 14, in line with the axis of the disk 20, is a shaft 31 arranged to both turn and slide in its bearing in said standard. On this shaft is an arm 65 32, and on this arm is a pin 33 adapted to engage the stop pin 30. On the shaft 31 is a spring 34 which serves to hold the arm 32 with the pin 33 in contact with pin 30, and also to hold the shaft 31 to the left as 70 seen in Figs. 1 and 2. On the bed 11 is a magnet 35 provided with an armature 36 arranged to strike an adjustable nut or collar 37 on shaft 31 and move said shaft longitudinally when the magnet is energized. 75

Secured on the arm 32 is a socket 38 in which is a pin 39 which is in line with the holes 21 in disk 20. When in normal position the parts are as shown in Fig. 4 and in full lines in Fig. 8. When the magnet 35 80 attracts its armature, the shaft 31 and arm 32 are moved to the right as seen in Figs. 1 and 2. This brings the pin 33 against a small block 40 (Fig. 8) which is secured to arm 29 under pin 30. It also brings the end of pin 39 against the face of the constantly rotating disk 20 to slightly deflect spring 41 as shown in Fig. 5. As soon as a hole 21 in disk 20 registers with the pin 39, the spring 41 projects said pin into such 90 hole, and thereafter the arm 32 turns with the disk 20. In this condition the pin 33 (Fig. 8) moves downward on the face of block 40, and as soon as it reaches the lower edge of said block, the parts move from the 95 full line to the dotted line position. This movement is under the action of the magnet 35 which keeps a longitudinal strain on shaft 31 during this movement of arm 32. The parts in Fig. 6 correspond to the dotted 100 line position shown in Fig. 8.

When the circuit is broken thru magnet 35, the spring 34 returns shaft 31 to the left, and this frees the pin 39 from the disk and

permits spring 34 to rotate the shaft back to normal position with pin 33 in contact with pin 30.

Adjacent to the magnet 35 are some contact springs which are operated by the successive movements of the shaft 31. The first movement, due to an impulse going thru magnet 35, breaks the connection between one pair of springs but is without effect upon the other springs. The shaft movement due to pin 33 slipping from block 40 shifts the electrical connections of the other springs. This matter will be further described in connection with the operation.

On the arm 32 is an insulated contact maker or wiper 42 arranged to make contact with pins 28 when the arm is rotated in the manner described. The pins 28 are twice as numerous, within the space occupied by them, as the holes 21 in disk 20. In other words, the wiper 42 engages two pins 28 during the time the disk is moving the distance equal to that between one hole 21 and the next adjacent one.

At the right in Figs. 1 and 2 are some contact springs shown in elevation in Figs. 9 and 10. These springs are operated back and forth once during each revolution of shaft 15. This will be further described in connection with the description of the operation.

In addition to the apparatus described, there are at the central office a series of keys used in making calls on a party line, a series of magnets controlled by the keys, cord circuits, and generators. Also, at the central office, in connection with each party line, are a jack, a drop and a mechanism which operates synchronously with the mechanisms at the local stations on the line. These last are substantially the same as those shown in my former Patent No. 1,326,212, dated December 30, 1919. The slight difference between the previous mechanism associated with each party and the present one will be set forth in the description of the apparatus. A party line may have any number of local stations thereon, and the central office apparatus will include connections for all of these stations. In Fig. 11, however, I have shown connections for only three stations, it being understood that other connections of the same kind, and connected in the same way, are used for additional stations.

It will be assumed that the operator at the central office wishes to call the subscriber at station No. 2, illustrated arbitrarily by a circle in the upper part of Fig. 11. She begins by inserting the plug 44 into the jack of the line wanted, by pressing K, and by pressing the key B² on her keyboard which would correspond to station No. 2. A current then flows as follows: generator X—45—46—47—relay 48—49—

50—51—52—53—54—55—56—57—58—59—60—relay A²—61—62—metal band on key B²—63—64—65—66—67—X.

The consequent operation of relay A² shifts the adjacent springs, one part of which consists in this relay closing a branch circuit for itself independent of key B², as follows:—61—68—69—70—71—66—67—X.

The operation of the relay 48 shifts its adjacent springs, one effect of which is to close a branch circuit as follows:—47—72—73—74—lamp 75—65—66—67—X.

Another effect of the operation of relay 48 is to connect the generator X to one side of the party line, whereupon a current flows as follows:—X—45—76—77—ground to all of the local stations on the line—78—79—80—81—82—83—84—85—86—87—88—relay 89—90—91—92—67—X. There is a branch of this which goes thru the magnet 193 to operate the adjacent mechanism in the same way that the mechanisms at the several local stations are operated. This is in release direction thru the local station mechanisms and is designed to insure that those mechanisms shall be at their normal positions before operating impulses begin. This release impulse is repeated, for a brief period, once for each revolution of the shaft 15.

The impulse described thru the relay 89 breaks the connection between 56 and 57 which is in a shunt around the magnet 35. This puts the magnet 35 in series with the relays 48 and A² from the wire 52 to the wire 59. The consequent operation of magnet 35 moves the shaft 31 (Figs. 1 and 2) a short distance to break the electrical connection between springs 53 and 54, but not between the other adjacent springs. This is a second break in the shunt around magnet 35 and provides that the circuit for that magnet will not be affected when it is broken thru relay 89 at springs 76 and 92.

The preliminary movement of the shaft 31 is quickly followed by a hole 21 in disk 20 coming opposite the pin 39 carried on the arm 32. When this occurs the arm 32 is carried with the disk 20 until the pin 33 slips from contact with the block 40. Upon the occurrence of this action the shaft 31 is moved longitudinally to shift spring 86 from 87 to 95, whereupon impulses flow as follows:—X—45—76—93—94—95—86—85—84—83—82—81—80—79—78—magnet 193 and similar magnets at all of the local stations on the line—ground—105—92—67—X. These are impulses in the operating or stepping up direction and serve to advance the various switching mechanism from their normal positions.

From the above it will be seen that the shift from impulses in the release direction to impulses in the stepping up direction occurs when the shaft 31 makes its final move-

ment under the action of magnet 35 as a result of pin 33 slipping from block 40. The wiper 42 is so set that it engages the first pin 28 just after the fourth stepping up impulse. In other words, the first three of these impulses are idle and the fourth becomes the first as far as operating is concerned. This is for the purpose of accommodating details of local station apparatus which are not herein described because they have no bearing on the present invention. The pins 28 are so arranged that the first two correspond to the relay A' and consequently to station No. 1 on the line. The next two pins 28 correspond to relay A² and station No. 2 and so on.

When the wiper 42 engages the upper pin 28 of the first pair, nothing occurs as the connection to that pin is open by reason of the relay A' not being operated. When the wiper engages the lower pin of the first pair, nothing occurs because the connection is open at the lower spring of relay A² by reason of that relay having been operated as a consequence of depressing key B². When the wiper 42 reaches the upper pin of the pair associated with A² and B², a current flows:—X—45—46—47—relay—106—107—108—109—110—111—112—42—113—71—66—67—X.

Normally the springs 96 and 97 connect the tip and sleeve sides of the cord together after the relay 48 has operated, and consequently connect together electrically the two limbs of the line reaching the local station. When the relay 106 operates it cuts this shunt by opening springs 96—97. In this operation the spring 97 connects ground to the sleeve side of the cord, and this occurs when the generator X has its negative side connected to ground. Under these conditions a current flows:—X—45—76—93—94—95—86—85—84—83—82—81—80—79—78—local station No. 2 (which is the one having its mechanism set for the second operating impulse)—104—103—102—101—100—99—98—97—97^a—ground—105—92—67—X. This is an impulse thru the cut-in coil of the selected station and serves to connect that station telephonically to the line in the manner well known in the art.

By comparing the circuit just given thru the cut-in coil of the local station with the previously given circuit thru the operating coil it will be seen that the two are the same except that the operating impulse goes to ground at the local station whereas the cut-in impulse goes back over the wire 104 and reaches ground at spring 97^a. In other words, the stepping up magnet and the cut-in coil of the local station, are in parallel in a circuit closed by the cam 16, the branch including the cut-in coil being closed by the relay 106 when the wiper 42 engages the first pin associated with the relay A². This

branch is closed a little later than the branch thru the stepping up magnet, but while the stepping up branch is held by reason of the width of the face of the cam 16. Hence, this latter is not a new impulse thru the stepping up magnet.

When the wiper 42 reaches pin 114, which is the second pin of the second pair, the line is open at spring 115 by reason of the action of relay A² shifting its springs. But there is a connection 116 extending from spring 115 to the spring 117 associated with relay A³, which spring is in contact with spring 118 when A³ has not been operated. The wire 116 corresponds to the wire 120 which connects spring 119 of relay A' with spring 121 of relay A². Similarly, there is a wire 122 which extends to a spring on the next relay (which would be A⁴) that corresponds to the springs 119, 115 and 117. In the same way connections are made step by step thru corresponding springs for as many relays as are used in the arrangement.

From the corresponding spring of the last relay there is a connection 125 to relay 124. As only three relays A are shown this wire extends from connection 126. Consequently, when the wiper reaches the pin 114, which is the second pin of the second pair, a current flows:—X—45—46—47—124—125—126—118—117—116—127—114—42—113—71—66—67—X.

The actuation of relay 124 breaks the connection between springs 50 and 51, which is in the circuit for magnets 48, A² and 35, thereby permitting their armatures to fall back to normal positions.

When the armature of A² falls back it breaks the circuit for 106 at spring 109. When the armature of magnet 35 falls back it permits the arm 32 to be freed from the disk 20 so that spring 34 may return these parts to normal position. This action breaks the circuit for 124 at the contact pin 114. This leaves the selected station No. 2 connected to the cord, and all electrically operated devices at the central office in their normal positions.

When the armature of 48 falls back, it connects the ringing generator G to the ringing commons 82 and 101 thru connections readily traced. As the operator is presumed to have the key K depressed at this time, ringing current flows over line limbs 78 and 104 to station No. 2.

The above represents what occurs when one person on the line is connected telephonically thereto. It will now be assumed that it is desired to connect stations 1 and 3 to the line at the same time by reason of the fact that the subscriber at one of these stations wishes to talk to the subscriber at the other.

The operator inserts the plug 44 and presses the key K as before. She also presses keys B¹ and B³ representing stations Nos. 1

and 3. Current flows: X—45—46—47—48—49—50—51—52—53—54—55—56—57—58—59—60—A'—128—129—B'—130—64—65—66—67—X. Also a branch from 60—A³—5—131—132—B³—133—64, etc. Also a branch thru the lamp 75, closed by 48 as before.

The relays A' and A³ close for themselves at their top springs as previously described for A². The sequence of events after this is 10 the same as described before until the wiper 42 engages the first pin. When this occurs, a current flows: X—45—46—47—106—107—134—135—136—137—138—42—113—71—66—67—X.

15 This connects spring 97^a to ground so that an impulse flows over the two limbs of the line to operate the cut-in coil at station No. 1 and connect that station telephonically to the line. When the wiper 42 engages the 20 second pin, the connection therefrom which goes thru 120, 115 and 116 is found open at 117 because pressing key B³ caused A³ to shift its springs. Consequently nothing happens when the wiper engages the second pin. 25 Also, nothing happens when the wiper engages pins 112 and 114 as will be readily seen by remembering that A² has not been operated and A³ has.

30 When the wiper 42 engages pin 123, another impulse flows thru relay 106 as before, except that it goes by the way of the springs of A³ instead of by the way of springs of A' or A². As before, the effect is to send an impulse thru the cut-in coil of station No. 35 3 to connect that station telephonically to the line.

When the wiper reaches pin 39, which is 40 the second pin associated with the highest numbered station, an impulse flows as before thru 124 which in turn breaks the circuit thru 48, A' and 35, and results in connecting generator G to the line.

45 By referring back to the previous descriptions it will be seen that when the operator depresses any key B, a circuit is closed thru the relay 48 and thru the particular relay A which corresponds to the key B depressed. The actuation of the relay 48 closes a branch of this circuit thru the lamp 75. 50 This branch remains closed as long as a current flows thru relay 48, and such current continues to flow as long as a key B is depressed except for the break accomplished by the subsequent action of relay 124. Consequently, the burning of the lamp 55 indicates that a key B is depressed.

60 While the current is flowing steadily thru relay 48 and lamp 75 in parallel, release and operating impulses flow thru another branch 65 from the same source and find ground at a plurality of stations. The source X and the resistances in the various branches are so related to each other that each impulse thru the magnets of the local stations draws on the source enough to dim the brilliancy of

the lamp 75. As a consequence, the flickering of the lamp shows to the operator that the system is operating properly. When finally the branch circuit thru lamp 75 is broken by reason of the armature of 48 falling back the lamp goes out and the operator releases the depressed key B.

67 70 As previously stated, release and stepping up (operating) impulses which go thru the local stations also go thru the magnet 193. Stepping up impulses thru this magnet advance the ratchet wheel 140 step by step. On the shaft of the wheel 140 is a cam 141 which acts to shift a spring 142 from contact 143 to contact 144 when the wheel is 80 advanced.

When release impulses flow thru magnet 193, the armature lever moves in the opposite direction and serves to release the holding pawl 145. The holding pawl has a downwardly projecting arm so arranged that the pawl and arm taken together form the pallet of an escapement. On the lever side of the wheel are two projections 146 which are normally within the lower arm of the pallet but which move beyond that arm when the wheel is advanced. When release impulses flow thru magnet 193, the first impulse permits the wheel to return until the first projection engages the pallet. The second impulse permits it to return until the second projection engages the pallet, and the third impulse releases the second projection. In other words, it requires three release impulses to fully release this apparatus, which 90 differs from the apparatus at the local stations in that those do not have the projections 146 and are normally fully released by a single release impulse.

95 100 105 When the subscriber is thru talking he signals the central office in the ordinary manner, and the operator removes the plug 44. Thereupon an impulse flows:—X—45—76—77—ground to all local stations on the line and to magnet 193—78—79—147—142—144—90—91—92—67—X.

110 115 120 This is an impulse in the release direction and permits the apparatus at the several stations to return to normal position. But the wheel 140 does not fully return to normal by a single impulse by reason of the projections 146, and spring 142 is held against contact 144 by cam 141 until such return is complete. As a result, another release impulse is sent each time that the shaft 15 makes a revolution until the release is complete.

125 130 135 Normally, the apparatus at the local stations is completely released by a single release impulse, but the best apparatus will sometimes get stuck for some reason or other and can be released by repeated jarring or by taking it apart to see what the trouble is. These repeated release impulses are for the purpose of insuring complete release in case a single release impulse should fail to ac-

complish that result. The release impulses which are first sent out when a key B is depressed are also for the purpose of making certain that all apparatus is at normal position before stepping up begins.

In some central offices, particularly in rural districts, there is only one operator, and it is sometimes necessary for her to be absent. In such cases it is desirable to temporarily eliminate the lock out restrictions, and make the line open or free for all persons on it. To bring about this result, the operator presses the last key B and causes an impulse to flow thru 48 and last relay A. This starts the previously described operations which lead to the wiper 42 engaging the pins 28. After pressing the last key B and before the wiper 42 begins making its contacts, she presses the key C which closes a readily traceable branch circuit for the relay 106. This connects 97^a to ground so that when the wiper 42 engages the second pin of each pair a cut-in impulse flows thru the cut-in coil of the corresponding station so as to connect all stations telephonically to the line. She holds key C depressed until the light goes out.

When the operator later returns, she presses the release key R which closes a circuit thru relay 48 without closing it thru any station controlling relay. This circuit is as follows:—X45—46—47—48—49—50—51—148—149—150—64—65—66—67—X. The effect of the actuation of 48 is as before to send a series of release impulses thru the local stations. This time, however, the release impulses are not followed by stepping up impulses because the branch which goes thru the magnet is not closed by depressing some key B.

On the keyboard is a key M, which is shown without electrical connections. This is a key for starting the generator X, the details of the circuit of which are not material to the present invention.

Referring back to Fig. 8 it will be seen that the pins 30 and 33 have beveled ends. When the shaft 31 is moved axially to lock the arm 32 to the constantly revolving disk 20, the pin 33 is moved away in the arc of a circle from the pin 30, but is not moved away axially. After the required stepping up impulses are completed, the circuit is broken thru magnet 35 and spring 34 moves the shaft 31 back to free the arm 32 from the disk 20. But if for some reason the parts get stuck and the spring 34 fails to release arm 32, then the pin 33 will continue to travel in a circle until the bevel on pin 33 strikes that on the stationary pin 30, whereupon the wedge action of one upon the other will mechanically force the shaft 31 backward to release arm 32.

As previously stated, the two limbs of the line are connected together between the time

the relay 48 operates and the time the relay 106 to connect for a cut-in coil. As a consequence, if any not wanted subscriber should operate his generator during the time his apparatus was going over his cut-in contact, the current from the generator would not operate his cut-in coil because the connection between the line limbs makes a shunt which prevents such operation.

What I claim is:

1. In a party line system, a line having a plurality of stations connected thereto, a plug and jack by which the line is connected to a central office, means for sending operating and release impulses over the line to control the telephone connections of the station thereon, and automatically operating means by which a plurality of release impulses are caused to flow over the line when the plug is removed from the jack.

2. An apparatus arranged to be advanced step by step by impulses flowing in one direction and to be released by an impulse flowing in the opposite direction, and means by which upon the apparatus not becoming fully released by one release impulse other release impulses will automatically continue to flow until such release is complete.

3. An apparatus arranged to be advanced step by step from normal position by electrical impulses in one direction and to be released by impulses in the opposite direction, means for sending a series of release impulses, and automatically operating means by which such impulses are interrupted when the apparatus reaches normal position.

4. In a telephone exchange, a party line connected to a central office, means for sending impulses over the line to operate devices at local stations thereon, an electrical device operated after the initiation of said impulses to cause a special impulse serving to connect a selected station telephonically to the line, and means by which the two limbs of the line are held in electrical connection with each other during the interval between the initiation of said impulses and the operation of said electrical device.

5. The combination with a central office, a party line having stations thereon, and a source of electrical impulses, of means for connecting the two limbs of the line together at the central office and for connecting said source to one of said limbs so that impulses may flow through the stations on said line, and means by which upon disconnecting the line limbs at the central office an impulse will flow through another part of one of said stations to connect it telephonically to the line.

6. The combination with a party line having a series of local stations thereon, a source of electric current, and means for closing for a successive number of times a

circuit having branches through the several stations, of means for closing a second branch of said circuit through a selected one of said stations during the time the circuit 5 is closed through all of them.

7. A party line connected to a central office, a source of electric current, devices for sending a series of impulses over said line and through the stations thereon, a lamp 10 located in a separate circuit and lighted when such impulses begin and extinguished when they cease, and means by which the correct operation of said devices is indicated by fluctuations in the light from said lamp.

15 8. In a telephone exchange, a source of electricity, a lamp, electrical devices at local stations on a party line, a circuit from said source and having branches through said lamp and said stations, and an interrupter 20 in the branch leading to the stations said parts being so arranged that the operation of the interrupter affects the quantity of current flowing thru the lamp without interrupting the same.

25 9. The combination with a central office, a party line connected thereto, and a source of electricity, of a constantly running body, a contact maker, means for moving said contact maker to engagement with said body 30 and into a path in which it will make electrical connections, means by which impulses from said source will flow over said line in a release direction when the contact maker is first moved, and means by which the impulses from the source will be changed to a stepping up direction over said line when the contact maker reaches said path.

10. The combination with a party line, a central office, and a source of electricity, of 40 a contact maker, a magnet arranged when actuated to start a series of mechanical operations one of which consists in moving said contact maker over a series of stationary contacts, and means controlled through said 45 contact maker and one of its stationary contacts for breaking the circuit for said magnet to stop said series of operations.

11. In a controlling mechanism for sending impulses over a party line, a continuously operating device arranged to make 50

and break electrical connection at regular intervals of time, a disk geared to said device so as also to be continuously moved, said disk having connecting points, a normally idle contact maker, and means for connecting said contact maker to one of said connecting points so as to move it. 55

12. A device arranged to continuously make and break electrical connections, a perforated disk connected to said device so that the disk will move the distance between one perforation and the next while the device is making one cycle of operations, a normally idle contact maker, and means for connecting said contact maker to said disk 60 at one of said perforations. 65

13. The combination with a party line, a device for sending electrical impulses over said line at regular intervals, and means for connecting said device to said line, of a normally inactive device arranged upon actuation to send secondary impulses over said line, and automatically operating means for connecting the normally inactive device in a definite relationship to the first mentioned 70 device. 75

14. The combination with a party line, and a device for sending electrical impulses over said line, of two sets of contact springs each set having a normal relationship, a magnet arranged upon actuation to change the normal relationship of said springs, means by which said device controls the actuation of said magnet so as to cause the change in relationships of the two sets of 80 springs to be separated by an appreciable 85 interval of time, and means by which the second change causes a change in the impulses flowing over the line.

15. An impulse sending device, a magnet, 90 two sets of contact springs actuated by said magnet, means actuated by the sending device for controlling said magnet so as to cause the two sets of springs to be actuated at different times, and means by which the 95 actuation of the second set of springs operates to change the impulses sent by said device.
